UNITED STATES PATENT OFFICE.

FREDERICK A. ATKINSON, FRED PICKARD, AND OLIVER J. PICKARD, OF PHILADELPHIA, PENNSYLVANIA, ASSIGNEES TO JOSEPH PICKARD'S SONS CO., A PARTNERSHIP CONSISTING OF OLIVER J. PICKARD, FRED PICKARD, AND FREDERICK A. ATKINSON, ALL OF PHILADELPHIA, PENNSYLVANIA.

FILE WIRE.

Application filed May 14, 1926. Serial No. 109,091.

This invention relates to pile wires of the type including a pile shearing blade at one end, and the principal object of the invention is to provide novel cutting means insuring effectiveness in shearing the pile loops.

A more specific object of the invention is to provide a pile wire with two blades arranged longitudinally of the wire so that in the event that one is inoperative the other will insure the cutting of the pile loops.

A still further object of the invention is to provide a primary cutting means in the form of a detachable blade which may be periodically renewed.

The invention further resides in novel means for retaining this detachable cutting blade in position in the pile wire.

In the attached drawings:

Figure 1 is a view of a pile wire made in accordance with our invention looking down upon the upper edge thereof;

Fig. 2 is a side view of that portion of the pile wire shown in Fig. 1;

Fig. 3 is a view of the detachable cutting blade;

Fig. 4 is a side view of the pile wire with the primary cutting blade removed, and

Fig. 5 is a section on the line 5—5, Fig. 2.

Referring to the drawings, the pile wire 1 may in general be of the usual form and may comprise at its end an integral elevation 2 presenting an inclined edge 3 adapted to be sharpened and to constitute a cutting edge. In the present instance, the extremity 35 4 of the wire is turned out transversely from the plane of the wire. The blade in so far as described is similar to the type of blade now in general use.

Adjacent the bottom of the cutting edge 3, the pile wire is provided in its upper edge with a longitudinal slot 5 adapted to receive a separately formed cutting blade 6, this blade being in the present instance substantially triangular in form and being

arranged in slots so that one edge 7 which is adapted to be sharpened inclines upwardly from the upper edge of the wire toward the adjacent end of the latter. In that edge which is opposite the cutting edge

7, the blade 6 is provided in the present instance with two slots 8, 8 which are adapted to receive a pair of pins 9, 9 extending transversely across the slot 5. The recesses 8 are inclined from the vertical so that the pressure of the pile loops against the cutting edge 7 in the normal manipulation of the pile wire will have a tendency to wedge the blade more tightly in the slot 5 and against the pins 9 whereby the tendency for the blade to be forced out of the slot is eliminated. After insertion of the blade 7 in the slot 5, the sides of the latter may be pinched in at both ends of the blade, as indicated at 11, 11, so that the blade is more or less positively held in the slot. Removal of the blade when desired, however, is not prevented, and the blade may be replaced without trouble when such replacement is found necessary. It will be noted that with this construction two cutting edges or blades 3 70 and 7 are provided, the primary cutting edge or the one which normally severs the pile loops being detachable to permit renewal.

We claim:

1. A pile wire having adjacent one end a plurality of cutting edges arranged longitudinally of the wire, the primary cutting edge being separately formed and detachable from the wire.

2. A pile wire comprising at one end an integral upwardly inclined cutting edge and having adjacent said cutting edge a slot in the upper edge thereof for the reception of a second and independently formed cutting blade.

3. A pile wire comprising in its upper edge a slotted recess for the reception of a cutting blade, a pair of pins extending across said recess, and an independent cutting blade adapted to be mounted in said slot and having in its under edge recesses for the reception of said pins.

4. A pile wire comprising a slotted recess in its upper edge provided for the reception of an independently formed cutting blade, a plurality of pins projecting across said recess, and a cutting blade having recesses

adapted to receive said pins, said recesses being inclined toward the top from the vertical toward that end of the cutting blade which in normal operation of the blade first comes in contact with the pile loops.

5. A pile wire having adjacent one end longitudinally aligned blades presenting in-

dependent cutting edges inclined upwardly from the top of the wire and toward the said end of the latter.
